UNITED STATES PATENT OFFICE.

JOHN DIERDORF, OF INDIANAPOLIS, INDIANA.

DESIGN FOR A PIANO-PLATE.

SPECIFICATION forming part of Design No. 31,277, dated July 25, 1899.

Application filed June 22, 1899. Serial No. 721,490. Term of patent 3½ years.

To all whom it may concern:

Be it known that I, JOHN DIERDORF, a citizen of the United States, residing at Indianapolis, in the county of Marion and State of Indiana, have invented a new and original Design for Piano-Plates, of which the following is a specification.

Figure 1 is a side elevation of my piano-plate, showing my new design; and Fig. 2 is 10 a sectional view taken on the line 2 2 in Fig. 1.

As shown in the drawings, the leading or material features of my design consist, first, of the openings in the upper portion of the plate, as indicated at A and B, and, second, 15 of a cross strengthening and sounding rib C, which is formed integrally with the plate

proper. Fig. 2 shows the outline of the rib and its points of connection with the main body of the plate.

Having thus fully described my said invention, what I claim as new, and desire to secure by Letters Patent, is—

The design for a piano-plate, as herein shown and described.

In witness whereof I have hereunto set my hand and seal, at Indianapolis, Indiana, this 1st day of March, A. D. 1899.

JOHN DIERDORF. [L. S.]
